US00D534175S

(12) **United States Design Patent** (10) **Patent No.:** **US D534,175 S**
(45) **Date of Patent:** **** Dec. 26, 2006**

(54) **FACSIMILE TRANSMITTER-RECEIVER**

(75) Inventors: **Miyabi Orihashi**, Tokyo (JP); **Hiroaki Ohashi**, Tokyo (JP)

(73) Assignee: **Canon Kabushiki Kaisha**, Tokyo (JP)

(**) Term: **14 Years**

(21) Appl. No.: **29/243,078**

(22) Filed: **Nov. 21, 2005**

(30) **Foreign Application Priority Data**

Aug. 23, 2005 (JP) 2005-024205

(51) **LOC (8) Cl.** **16-03**

(52) **U.S. Cl.** **D14/463**

(58) **Field of Classification Search** D14/462-471;
358/400-402; D18/36, 37

See application file for complete search history.
